United States Patent Office

Des. 227,597
Patented July 3, 1973

227,597

SPECTACLE FRAME FRONT

Anthony Shindler, Brookline, Mass., assignor to American Optical Corporation, Southbridge, Mass.

Filed June 16, 1971, Ser. No. 153,907

Term of patent 14 years

Int. Cl. D16—06

U.S. Cl. D57—1 F

FIG. 1

FIG. 2

FIG. 3

FIG. 4

FIG. 1 is a front elevational view of a spectacle frame front embodying my new design;

FIG. 2 is a top plan view thereof;

FIG. 3 is a side elevational view thereof, the opposite side having the same appearance; and

FIG. 4 is a left front perspective view thereof.

I claim:

The ornamental design for a spectacle frame front, as shown and described.
